Attorney

UNITED STATES PATENT OFFICE.

IRA FUSON, OF LONG BEACH, CALIFORNIA.

SINK STRUCTURE.

Application filed March 24, 1925. Serial No. 18,025.

This invention relates to sink structures and more particularly to the structure of the ordinary type of kitchen sink.

An important object of the invention is to provide a sink having means for supporting a garbage pail in such manner that the sink may act in effect as a funnel for the garbage pail preventing spilling of the contents of the garbage pail upon the floor.

10 A further object of the invention is to provide a device of this character enabling ready removal from the sink of those particles of garbage washed from dishes and the like and collecting upon the usual drain of the sink.

15 These and other objects I attain by the construction shown in the accompanying drawings, wherein for the purpose of illustration is shown a preferred embodiment of my invention and wherein:

20 Figure 1 is a plan view of a sink constructed in accordance with my invention;

Figure 2 is a side elevation thereof; and

25 Figure 3 is an enlarged detailed sectional view through the sink at the point where the opening is formed therein.

Referring now more particularly to the drawings, the numeral 10 indicates a sink having the usual drain outlet 11. Adjacent the opposite end of the sink, an opening 12 is formed through the bottom of the sink, this opening being preferably about four inches in diameter. Upon the bottom of the sink are formed spaced horizontally directed and transversely extending and opposed flanges 13, each having inwardly directed horizontal ribs 14. A pail 15 is provided having at its sides outstanding flanges 16 adapted to overlie the horizontal portions 14 of the flanges 13 and thereby support the pail. This pail is preferably of considerably greater size than the opening beneath which it is placed. For example, where a four inch opening is provided, as stated above, it is preferred that the diameter of the pail at the flange should be at least ten inches. For the opening, a plug closure 17 is provided having a sealing fit in the opening and preferably having a flexible flange overlying the edges of the sink at the sides of the opening which may come into close engagement with the surface of the sink.

It will be obvious that with a structure of

this character, it is possible to use the usual flexible cap for the drain opening of the sink and employ the sink as a receptacle for wash-water as it is often employed. It will furthermore be obvious that when crumbs or other particles of refuse collect at the drain when emptying dishwater or the like in the sink, they may be readily removed to the garbage pail without the necessity of collecting them in the hand and moving them to a garbage pail arranged upon the floor, which method of handling results in dripping of water upon the floor and in dropping of some of the particles upon the floor adjacent the sink. It will furthermore be obvious that in placing the garbage in the pail, the sink will act as a funnel and prevent any particles of the garbage from falling to the floor which is also a common occurrence where the garbage pail is simply placed upon the floor. Since the method of suspending the pail and the arrangement of the opening are both obviously capable of a considerable range of modification, I do not limit myself to the specific structure hereinbefore set forth except as hereinafter claimed.

I claim:

1. In combination with a receptacle adapted for the reception of articles to be cleansed by or treated with liquids, the receptacle having a drain opening and a further opening in spaced relation to the drain opening, a second receptacle adapted for the reception of solids, said first and second receptacles having coacting flanges engaging to support the second receptacle from the first named receptacle and beneath the second opening and means for sealing said second opening against the passage of liquids the receptacle being removable without disturbing the sealing means.

2. In combination with a sink having the usual drain opening and a further opening formed therein in spaced relation to said drain opening, a garbage receptacle, means for removably securing the garbage receptacle beneath the second opening of the sink and means for sealing said second opening against the passage of liquids.

3. In combination with a sink having the usual drain opening and a second opening in spaced relation to said drain opening, a seal-

ing cover for the second opening, a garbage receptacle of greater diameter than said second opening, said garbage receptacle being provided with diametrically opposed flange portions and opposed flanges extending across the under surface of the bottom of the sink at opposite sides of said opening and

adapted for the reception of the diametrically opposed flanges of the garbage receptacle to support the same.

10

In testimony whereof I hereunto affix my signature.

IRA FUSON.
